C. L. PELTON

MATERIAL DISTRIBUTOR FOR AIRCRAFT

Filed July 9, 1925

Inventor

Clifford L. Pelton.

By Robert H. Young

Attorney

UNITED STATES PATENT OFFICE.

CLIFFORD L. PELTON, OF BALTIMORE, MARYLAND.

MATERIAL DISTRIBUTOR FOR AIRCRAFT.

Application filed July 9, 1925. Serial No. 42,406.

To all whom it may concern:

Be it known that I, CLIFFORD L. PELTON, citizen of the United States, residing at Baltimore, in the county of Baltimore and

5 State of Maryland, have invented certain new and useful Improvements in Material Distributors for Aircraft, of which the following is a specification.

This invention relates to a distribution 10 apparatus for use on aircraft and more particularly concerns an apparatus for distributing materials in the form of smoke or powder which is intended to be scattered over the ground or in the air.

15 The primary object of the invention is the provision of an apparatus of this character by which material may be distributed over a considerable area with great rapidity and positiveness. The invention concerns 20 primarily a tube which is adapted to rotate at fairly high speed and distribute the material by the action of centrifugal force through a conduit extending radially within this tube.

25 Further objects and advantages of my invention will be more fully set forth in the following description and claims and in the drawings in which—

Figure 1 is a side elevation of an aircraft 30 with the rear part of the fuselage broken away showing the distributor applied thereto;

Figure 2 is a section taken through the distributing tube and

35 Figure 3 a corresponding view showing modification of my invention in which two materials are adapted to be co-mingled before or at the time of their distribution.

Referring more particularly to the drawing 40 by reference numerals, 1 indicates a fuselage of an aircraft which is provided with the usual sustaining surfaces and propelling means indicated at 2 and 3. Mounted in a central portion of the plane is a main receptacle 4 which is adapted to contain or hold a quantity of the material which is to be distributed from the aircraft. Extending from a lower portion of this receptacle and leading rearwardly is a passage 5 which conveys the material from the 45 receptacle to a rotatable pipe 6 which is suitably mounted by means of bearings 7 and 8 in a fixed casing 9. The casing 9 is adapted to be rigidly held in a suitable position at the rear or at a low portion at the

rear of the fuselage, and may be either vertically mounted or, as in the case shown, may be horizontally mounted within the fuselage.

The pipe 6 is made rigid with a rotatable 60 blade shaped tube 10 by means of a suitable set screw 11. This tube 10 in the case shown, is in the form of a two bladed impeller or propeller which is adapted to be rotated by the air as the craft travels there-through or which may be rotated through any mechanical means so as to revolve at a comparatively high rate of speed. A conduit 12 extends radially outwardly from the center of the tube or blade and is in com- 65 munication at its inner end with the interior of the pipe 6 so that material may be thrown outwardly by the action of centrifugal force as the tube rotates, this material being taken or withdrawn from with- 70 75 in the pipe 6 to which it is connected.

The pipe 6 in revolving is adapted to cause the passage of the material there-through by the provision of means such as the internal vanes 12 which have a tendency 80 to force the material to the rear so that it may be supplied to the rotating tube 10. The flow of material through the passage 5 is controlled by butterfly valve 13 which is manually operated by means of a rod 14 85 which extends to the aviator's cock-pit.

In case two or more materials are intended to be co-mingled or mixed together at the time or just before their distribution to the atmosphere an additional passage designat- 90 ed 15 in Figure 3 may be provided so as to communicate with the interior of the pipe 6 by means of an opening 16 provided there-in. It is to be understood that the pipe 15 may be provided with a valve which may 95 be controlled simultaneously with the valve 13 provided in the passage 5.

I am aware that my invention is capable of numerous embodiments and applications and desire that the particular form of my 100 invention which has been chosen for purposes of illustration should be considered merely as an example thereof.

I claim:—

1. In an aircraft, in combination, a receptacle for holding a quantity of material to be distributed from the aircraft, a tube rotatable about an axis on the aircraft, a conduit in said tube extending outwardly from said axis, a passage from said recep- 105 119

tacle to said tube, and means for rotating said tube to cause the material to be scattered in the air.

2. In an aircraft, in combination, a receptacle for holding a quantity of material to be distributed from the aircraft, a tube rotatable about an axis on the aircraft, a conduit in said tube extending outwardly from said axis, a passage from said receptacle to 10 said tube, and means for rotating said tube to cause the material to be scattered in the air, said tube having the form of a propeller blade.

3. In an aircraft, in combination, a receptacle for holding a quantity of material to be distributed from the aircraft, a blade shaped tube rotatable about an axis on the aircraft, a conduit in said tube extending outwardly from said axis, a passage from 20 said receptacle to said tube, means for ro-

tating said tube to cause the material to be scattered in the air, and means for controlling the flow of material to said tube.

4. In an aircraft, in combination, a receptacle for holding a quantity of material to be distributed from the aircraft, a tube rotatable about an axis on the aircraft, a conduit in said tube extending outwardly from said axis, a passage from said receptacle to said tube, said passage including 25 a pipe rotatable about said axis and rigidly connected to said tube, means within said pipe to convey the material along said pipe as the pipe rotates, and means for rotating said tube to cause the material to be scattered in the air through centrifugal force.

In testimony whereof I affix my signature.

CLIFFORD L. PELTON.
